UNITED STATES PATENT OFFICE.

EDWIN R. PROBERT, OF COVINGTON, KENTUCKY, ASSIGNOR TO THE MOESCHL-EDWARDS CORRUGATING COMPANY, OF COVINGTON, KENTUCKY, A CORPORATION OF KENTUCKY.

METAL-WINDOW MEETING-RAIL.

1,163,365.

Specification of Letters Patent.

Patented Dec. 7, 1915.

Application filed March 13, 1915. Serial No. 14,259.

To all whom it may concern:

Be it known that I, EDWIN R. PROBERT, a citizen of the United States of America, and a resident of Covington, in the county 5 of Kenton and State of Kentucky, have invented a certain new and useful Improvement in Metal-Window Meeting-Rails, of which the following is a specification.

This invention relates to safety interlocking-formations along the meeting-rails of metal window-sashes whereby the undue entrance of fire, smoke, draft, dust, water and other deleterious elements is prevented and especially at the weakest or most vulnerable 15 point for such elements to enter a building-structure through a closed window.

The object is to provide the meeting-rails with deep frictionally-engaging tongues and grooves on both the upper and lower edges 20 of the rails and having an air-space or insulating-chamber between them to collectively and thoroughly offset the flames or smoke from a fire without.

The details of structure for carrying out 25 the said object of the invention herein will be fully hereinafter described and particularly pointed out in the claim.

In the accompanying sheet of drawings,— Figure 1 is a vertical diagram-section partly 30 in elevation, taken on the dotted line *a*, *a*, of Fig. 2, and showing my improved meeting-rail structure as applied to a pair or set of closed, hollow, sheet-metal window-sashes, the side-stiles of the latter being broken off 35 on lines near their respective meeting-rails; and Fig. 2 is an outside elevation of the type of metal window to which my invention is especially adapted.

1 indicates the upper-sash and 2 the lower- 40 sash both incased for vertical, sliding movement in a suitable frame composed of the usual upright-members 3, 3, sill 4 and head 5.

As my invention is especially adapted for use in connection with sheet-metal window- 45 structures formed with hollow walls and resultant or consequent insulator-chambers throughout, and, more particularly, intended to meet the rigid requirements of underwriters in the quest for protective-insurance on property in which the windows 50 are installed, I will now describe the details of the meeting-rail joint or closure just as

they appear in Fig. 1, and that form a most effective fire-retardant at the least consistent outlay.

The sheets or strips of metal used in forming each of the meeting-rails are identical, as both rails are alike except that the recess or groove for the glass-sheet in the meeting-rail A of the lower-sash is deeper 60 than the one in the meeting-rail B for the glass-sheet in the upper-sash and they are used in reverse-position for interlocking when the sashes are closed. It will, therefore, be necessary to minutely describe but 65 the outer one B of the rails and then set forth its application to the other or companion inner-rail A, especially when the two rails meet in the closed position of the 70 two sashes.

A sheet is bent or folded into hook-form 6 along one edge, and then right-angles at 7 into a vertical straight outer-wall 8; thence again right-angles at 9 into a short, horizontal top-limb 10; thence takes an imitation-molding curve 11 till it reaches a short horizontal top-bend 12; thence it is formed into a slightly tapered glass receiving groove 13; thence it passes onward into a horizontal top-limb 14 alined with limb 12; thence 80 it descends with a vertical fore-wall 15 till an angle 16 is reached, and thence into a right-angled upturned-edge 17.

A narrower strip of metal is used as a horizontal or bottom filler 18 between the 85 first-named hook-end 6 and the upturned-edge 17, and is bent into hook-form at 19 to interlock with said hook-edge 6, and then further bent along its opposite edge with a vertical downwardly-turned hook-edge 20 90 that interlocks with the said upwardly-turned edge 17.

A deep vertical tongue is provided by the interlocked hook-edges 17 and 20 that projects at a right-angle upwardly from the edge 95 of the bottom or filler member 18 that then extends inwardly toward the inner meeting-rail A.

The reverse order of the same parts or formations, (except in connection with the 100 glass-sheet grooves referred to above,) in the sheet-metal occurs in the meeting-rail A of the lower-sash and is enumerated to harmonize or correspond.

I provide a reinforcing filler or closure-guard between the upper and lower tongues C and D and form it with spaced walls E, E, and F, F, so as to provide an insulating air-chamber G for better protection against the transmission of heat from a fire raging without. This filler is of materially heavier material than that of the meeting-rails, (as distinctly shown by contrast in Fig. 1), and is composed of two sheets or strips of metal, one for the upper-sash rail 1 and the other for the lower-sash rail 2. These strips are each bent alike, and each begins with a right-angled member 21 that extends into a vertical side-wall E, thence into a flaring-limb H, thence into a deep-folded double-limb I that extends thence at J along the said flaring-limb H, and ends with a straight short end that laps on the outer face of the side-wall E for riveted-connection K. The contacting, flaring portions H and J space the vertical folded double-limb H away from the adjacent face of the meeting-rail to which the strip is riveted at K, whereby a deep groove or slit is provided for the interlapping engagement or seating of the tongue formed by the interlocked hook-edges 17 and 20. It will be observed that the vertical extensions or ends of the right-angled members 21 lie between the said interlocked hook-edges 17 and 20, and are firmly compressed together to make a stiff and strong tongue along the interlocking upper and lower edges of two diagonally-opposite cor-

ners of the fire-retardant hollow guard that intervenes between the two meeting-rails.

The drawings show space between the parts of the tongues and in the grooves at both sides of the tongues, but it is obvious that such space is not really present in the device itself and should not be, as the tongues should frictionally-engage the grooves to assure effective service when needed.

The heavier-metal hollow-guard forms a stiff and substantial reinforce between the two meeting-rails to assure the desired firm and tight interlocking of the tongues in the grooves thereof, and no fire can pass this guard when the full engagement of the tongues and grooves is effected.

I claim:—

In a metal window-structure comprising a pair of sashes, a pair of spaced meeting-rails on said sashes each having oppositely but inwardly disposed L-shaped or rectangular flanges on their outer edges and inclosing the space between said meeting-rails, a pair of metal strips one fitting in each of the L-shaped flanges, the opposite edge of each of said strips being offset from its corresponding meeting-rail to provide a recess for the reception of the extremity of the L-shaped flange of the other meeting-rail in said recess.

EDWIN R. PROBERT.
